REFRIGERATION ASSEMBLY

Carl E. L. Lipman, Chicago, Ill., assignor to Lipman Patents Corporation, Chicago, Ill., a corporation of Delaware

Application April 8, 1933, Serial No. 665,071
Renewed December 9, 1936

7 Claims. (Cl. 62—116)

This invention relates in general to refrigeration, and has more particular reference to small refrigeration units such as are adapted for household purposes.

5 In household refrigerators it is desirable that the maximum amount of space within the cabinet be available for use as a food storage compartment, that the lower end of the compartment be disposed some distance above the floor 10 for convenience and accessibility, that the entire unit be compact in structure, that it present a flat top upon which dishes and other articles may be temporarily set, and that the refrigerating apparatus be readily detachable from the cabinet 15 for convenience of shipment, assembly and repair.

My present invention aims to provide all of these desirable features in a construction which will be economical to manufacture and operate, and which will be efficient and durable in use.

For the purpose of facilitating understanding 20 of my invention I have illustrated a preferred embodiment thereof in the accompanying drawings from which, when considered in connection with the following description, the principles of my invention and many of its inherent advantages 25 should be readily appreciated.

Referring to the drawings:

Fig. 1 is a vertical sectional view through a 30 refrigeration assembly embodying my invention, Fig. 2 is a rear elevation thereof,

Fig. 3 is a sectional view of the assembly detached from the cabinet and embodying a different form of condenser,

Fig. 4 is a rear elevation of the assembly shown in Fig. 3, and

Fig. 5 is a transverse sectional view on the line 5—5 of Fig. 4.

By reference to Figs. 1 and 2 of the drawings it will be observed that the cabinet, with which my invention is associated, comprises a bottom 5 supported at a convenient height upon legs 6 and carrying four upright walls, the rear wall being designated as 7, the front wall as 8 equipped with the usual door 9 through which access to the storage chamber 11 is attained. The walls of the cabinet embody in their construction heat insulating material as is customary, but, in this instance, the storage chamber extends to the top of the cabinet which is left open.

An assembly comprising a closure for this opening, a frame structure and a refrigerating apparatus carried by the frame structure is adapted to be removably associated with the cabinet in a manner which will now be described.

The frame structure comprises a pair of rigidly

connected angle members 12 and 13, each bent into L-shape so as to provide a vertical leg disposed at the rear of the cabinet wall 7 and a horizontal leg disposed over the top of the cabinet. This horizontal leg is fixedly secured to and carries a closure 14, adapted to close the opening at the upper end of the storage chamber 11. A seal between the closure and the surrounding walls of the cabinet is effected by gasket 15 interposed between the upper end of the cabinet and the top 10 16 of the closure, and a further seal is provided by a gasket 17 interposed between the lower perimeter of the closure and a bracket 18 extending around the interior of the chamber.

The refrigerating apparatus carried by the frame structure comprises a motor condenser unit 19 supported upon a shelf or bracket 21 carried by the lower end of the frame structure, a condenser 22 carried by the frame structure near its upper end, an oil cooling coil 23 carried by the frame structure above the condenser, a receiver 24 mounted in a recess in the upper face of the closure, and an evaporator 25 suspended in the storage compartment from brackets depending from the lower face of the closure 14. Suitable piping, indicated generally by 26, connecting the compressor, the condenser, the receiver and the evaporator, affords a circulating system for the refrigerant in the usual manner, and the oil cooling coil 23 through which oil is circulated for cooling purposes to dissipate the excess heat units generated by the motor and compressor, is connected with the motor compressor unit by piping indicated generally by reference character 27. The details of the refrigerating apparatus need not be here further described as they are immaterial to the present invention.

When the assembly is combined in operative relation with the cabinet, the frame assumes the position shown in full lines in Fig. 1, in which the motor compressor unit is supported beneath the storage compartment, the evaporator is in the storage compartment, the upper end of the compartment is closed by the closure 14, and the condenser and oil cooling coil are supported at the back of the cabinet. When the cabinet is placed against a wall, as is customary, the space between the rear wall of the cabinet and the room wall provides a flue through which the air will circulate upwardly around the condenser and oil cooling coil whereby the same are cooled. These coils are supported in the frame structure between angle members 28 and 29 rigidly secured to the frame members 12 and 13 which also form the flue side walls.

In the form shown in Figs. 3 to 5 the condenser 32 is of hollow sheet metal construction extending vertically adjacent the back wall 7 of the cabinet. The metal walls are of corrugated formation as shown in Fig. 5 to afford increased condensing surface and provide vertical flues which facilitates air circulation. The top of the condenser is connected with the compressor by a pipe 33 and a pipe 34 connects the bottom of the condenser with the receiver 24.

When it is desired to disassociate the refrigerating apparatus from the cabinet for purposes of shipment, replacement or repairs, this may readily be accomplished in the following manner. First, the lower end of the frame structure is swung outwardly from the cabinet about its upward forward end as a fulcrum into the position shown in dotted lines in Fig. 1, in which position the motor compressor unit is withdrawn from beneath the cabinet, and the closure 14 is practically withdrawn from the cabinet. The whole assembly may then be removed by simply lifting the frame to free the closure from the cabinet, whereupon the assembly may be packed for shipment, or it is accessible for repairs if necessary. To reassemble the parts with the cabinet, a mere reversal of the described steps is followed. For appearance's sake the top of the assembly is preferably covered and concealed from view by a removable cover 31.

It will be apparent from the foregoing that I have provided a structure in which the motor compressor unit is disposed beneath the cabinet, the cabinet is spaced from the floor so as to be in the most accessible position, practically the entire cubical content of the cabinet is available for food storage purposes, and the refrigerating apparatus is carried by a frame structure so that, together with this structure, it is removable as a unit from the cabinet. The structural details illustrated and described may be varied within considerable limits without departing from the scope of this invention as defined in the following claims.

45 I claim:

1. The combination of a cabinet providing a storage chamber having a top opening, a removable closure for said opening, an L-shaped frame structure, one leg thereof overlying and secured to said closure and the other leg thereof extending downwardly at the back of the cabinet, a motor compressor unit supported beneath said cabinet from the lower end of said frame structure, a condenser carried by said frame structure at the back of the cabinet, and an evaporator suspended beneath said closure in said chamber, said assembly comprising said frame structure, closure, motor compressor unit, condenser and evaporator being removable as a unit from said cabinet upon outward swinging movement of the lower end of the frame structure about the forward edge of said closure as a fulcrum to withdraw said motor compressor unit from beneath the cabinet and subsequent elevation of the assembly to lift said closure from the cabinet opening.

2. The combination of a cabinet providing a storage chamber having an opening at its upper end, and an assembly maintainable by gravity in cooperative relation to the cabinet, said assembly including an L-shaped frame structure, a closure for said opening attached to one leg of said structure, and a refrigerating apparatus comprising a motor compressor unit, a condenser and an evaporator, and being removable as a unit from said

cabinet, one leg of said frame structure overlying the top of the cabinet and the other leg depending adjacent the rear wall of the cabinet and having the condenser mounted thereon near the top of the cabinet and the motor compressor unit supported thereby beneath the cabinet, said assembly being detachable from the cabinet by swinging the lower end of the frame away from the cabinet to withdraw the motor compressor unit from beneath the cabinet and then lifting the assembly to withdraw said closure from said opening.

3. The combination of a cabinet providing a storage chamber having an opening at its upper end, an assembly including an L-shaped frame, having one leg disposed outside of and in proximity to the rear wall of the cabinet and its other leg overlying the cabinet, a closure for said opening disposed beneath and attached to said overlying leg, an evaporator depending from said closure into said storage chamber, a condenser carried by said upright leg, and a motor compressor unit supported from said upright leg and disposed beneath the cabinet, the entire assembly being liftable as a unit from cooperative relation with said cabinet when the lower end of said frame has been swung away from the cabinet to withdraw the motor compressor unit from beneath the cabinet.

4. The combination of a cabinet providing a storage chamber having the top open, a removable closure for said opening, a frame structure having a horizontal portion extending over said opening and a vertical portion extending downwardly at the back of the cabinet, a motor compressor unit disposed beneath said cabinet and attached to the lower end of said frame structure, a condenser, and an evaporator suspended beneath said closure in said chamber, said assembly including said frame structure, motor compressor unit, condenser, and evaporator being removable as a unit from said cabinet upon outward swinging movement of the lower end of the frame structure to withdraw said motor compressor unit from beneath the cabinet and subsequent elevation of the assembly to lift said evaporator from the cabinet opening.

5. The combination of a cabinet providing a storage chamber having an opening at its upper end, and an assembly disposed in cooperative relation to the cabinet, said assembly including a frame structure having one portion extending over said opening and another portion extending downwardly in proximity to a vertical wall of said cabinet, and a refrigerating apparatus comprising a motor compressor unit, a condenser, and an evaporator, said apparatus being removable as a unit from said cabinet, the motor compressor unit being located beneath the cabinet and the assembly being detachable from the cabinet by swinging the lower end of the frame structure away from the cabinet to withdraw the motor compressor unit from beneath the cabinet and then lifting the assembly to withdraw said evaporator from said opening.

6. The combination of a cabinet providing a storage chamber having an opening in its upper end, an assembly including an L-shaped frame having one leg disposed outside of and in proximity to the rear wall of the cabinet and its other leg disposed over said opening, an evaporator suspended in said cabinet from said other leg, a condenser, and a motor compressor unit attached to the upright leg of the frame and disposed beneath the cabinet, the entire assembly

being separable as a unit from cooperative relation with the cabinet by swinging the lower end of said frame away from the cabinet to withdraw the motor compressor unit from beneath the cabinet and then lifting the frame structure to remove the evaporator from said opening.

5. 7. A refrigerating apparatus adapted for use with a cabinet having an open top storage chamber elevated above the base of the cabinet to 10 provide a machinery compartment beneath the chamber, said apparatus comprising a frame having one portion thereof disposed over the top of such cabinet and another portion disposed adjacent to a vertical wall of said cabinet, an evaporator attached to said first mentioned frame portion and adapted to be positioned in said

chamber through said open top, a compressor unit attached to said other frame portion and adapted to be positioned in said machinery compartment, said apparatus including the frame, the evaporator, and the compressor being 5 adapted to be cooperatively associated with said cabinet by first lowering said evaporator into the storage chamber through the top thereof and then swinging said compressor unit into said machinery compartment from the back thereof 10 and being adapted to be disassembled therefrom by first swinging said compressor unit outwardly from beneath said storage chamber and then elevating said frame to lift said evaporator from said chamber.

CARL E. L. LIPMAN.
